UNITED STATES PATENT OFFICE

111,126

DESIGN FOR A DRESS

Jacob Abbate, New York, N. Y.

Application July 29, 1938, Serial No. 78,942

Term of patent 3½ years

To all whom it may concern:

Be it known that I, Jacob Abbate, a citizen of the United States and a resident of the city of New York, in the county of New York and State of New York, whose post-office address is 1215 Fifth Ave., New York, city and State of New York, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1.

I claim:

The ornamental design for a dress, substantially as shown.

JACOB ABBATE.
